The ornamental design for a running board, as shown.

DESCRIPTION

FIG. 1 is a perspective view of a running board embodying the principles of the present invention;

FIG. 2 is a top view of the running board seen in FIG. 1; FIG. 3 is a front view of the running board seen in FIG. 1; FIG. 4 is a bottom side view of the running board seen in FIG. 1;

FIG. 5 is a back side view of the running board seen in FIG. 1;

FIG. 6 is a right side view of the running board seen in FIG. 1; and,

FIG. 7 is a left side view of the running board seen in FIG. 1.

In the drawings, the broken lines depict environmental subject matter only and form no part of the claimed design. Shade lines having a combination of long and short lines in the drawings show contour and not surface ornamentation.
